UNITED STATES PATENT OFFICE.

RAMON CAMPDERÁ AND FEDERICO AYALA, OF MEXICO CITY, MEXICO.

DESIGN FOR A PERFUMERY-BOTTLE.

55,024.

Specification for Design.

Patented May 4, 1920.

Application filed August 18, 1919. Serial No. 318,419. Term of patent 14 years.

To all whom it may concern:

Be it known that we, RAMON CAMPDERÁ and FEDERICO AYALA, subjects of the King of Spain, residing at Mexico city, Mexico, have invented a new, original, and ornamental Design for Perfumery-Bottles, of which the following is a specification, reference being had to the accompanying drawing, forming part thereof, in which—

Figures 1, 2 and 3, are side elevations of the bottle taken from different points.

We claim:

The ornamental design for a perfumery bottle, as shown.

In testimony whereof we have affixed our signatures.

RAMON CAMPDERÁ.
FEDERICO AYALA.
